UNITED STATES PATENT OFFICE.

JOHN MEIER, OF DALLAS, TEXAS, ASSIGNOR OF ONE-TWENTIETH TO FRANK RICHARD
AND ONE-TWENTIETH TO FRANK PEYROT, BOTH OF CHICAGO, ILLINOIS.

SUCTION-CUP FOR COTTON-PICKING MACHINES.

1,127,482.

Specification of Letters Patent.

Patented Feb. 9, 1915.

Application filed May 8, 1914. Serial No. 337,425.

To all whom it may concern:

Be it known that I, JOHN MEIER, a citizen of the United States, residing at Dallas, in the county of Dallas and State of Texas, have invented certain new and useful Improvements in Suction-Cups for Cotton-Picking Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in suction cups or heads for cotton picking machines and it relates particularly to suction cups designed for use in connection with that class of cotton picking machines in which the cotton boll is detached from the plant and carried through the suction chamber and it relates more particularly to means whereby the boll can be readily detached by the operator.

To these ends and to such others as the invention may pertain, the same consists in the provision of a cup of the character described in which the entrance to the cup is provided with a curved plate extending around the periphery of the entrance.

The invention is illustrated in the accompanying drawings, which form a part of this specification, and in which:

Figure 1 is a side elevation, partly in section, of a suction cup constructed in accordance with my invention. Fig. 2 is a plan view of the end of the cup, and Fig. 3 is a perspective view of a cutting blade.

Reference now being had to the details of the drawings by numeral, 1 represents a metallic tube provided at one of its sides with a suitable handle 2. One end of the said tube is designed to be attached to a

suitable cotton conveying tube leading to the suction chamber of the cotton picking machine. The free end of the tube has securely bolted thereto a head or chamber 3, the opposite end of which forms the entrance to the suction cup and provided with a peripheral, outwardly extending flanged portion 4 which is provided with screw receiving apertures. Semicircular knives 5, having elongated slots therein, are adapted, when placed together, to have a diameter equal to the diameter of the flange 4. Screws 8 are passed through the slots in the knives and engage the threaded holes in the flange and serve to securely hold the knives in proper position upon the device.

From the foregoing description, the operation of the invention will be readily understood.

The circular cutting edge of the plate 5, which extends entirely around the entrance to the cup, serves as a means whereby the operator, in picking the cotton, can, after the cup is placed over a cotton boll, cut the boll from the stem by imparting a lateral movement to the head.

Having thus described my invention, what I claim to be new and desire to secure by Letters Patent is:

A suction cup for cotton picking machines having a flange about one end thereof, semicircular knives having cutting edges upon their inner peripheries, and provided with slots, screws passing through said slots and apertures in the flanges, the cutting edges of the blades being flush with the face of said flange.

In testimony whereof I hereunto affix my signature in presence of two witnesses.

JOHN MEIER.
